UNITED STATES PATENT OFFICE.

EMIL JACOBSEN, OF PORT WASHINGTON, AND ARTHUR B. SPERRY, OF NEW YORK, N. Y., ASSIGNEES TO WESTERN ELECTRIC COMPANY, INCORPORATED, OF NEW YORK, N. Y., A CORPORATION OF NEW YORK.

TELEPHONE SYSTEM.

Application filed June 5, 1925. Serial No. 35,074.

This invention relates to automatic telephone systems and more particularly to a system arranged for extending calls from dial stations in a three-wire office to an intercepting operator's position of a two-wire office.

In certain existing step-by-step machine switching areas there have been installed step-by-step machine switching equipments designed to operate on the so-called three-wire basis, that is, controlling impulses from substation dials are directed over two circuits from the substation each comprising one of the talking conductors and a ground return. In such areas, when it becomes necessary to add additional equipment to care for the growth of the exchange, it is desirable and more economical to install equipment of a more modern character which is designed to function over full metallic circuits extending to the substations eliminating the ground return. When such modern equipment is added to an existing exchange it becomes necessary to provide means whereby the two types of apparatus may function together so that all subscribers may have access to each other's lines and to special service operator's positions.

The object of this invention is therefore to provide an improved means for handling calls from a dial station in a three-wire office to a dial station in a two-wire office including the feature that when such a call is routed to an intercepting operator in a two-wire office, means are provided for controlling the supply of talking battery to the calling subscriber in the three-wire office.

Fig. 1 of the drawings shows the subscriber's station A in the upper left-hand corner connected to a line switch LS, a three-wire first selector FS having brushes 3, 4 and 5 which has access to a three-wire repeater circuit R shown in the center of this drawing. The repeater circuit is connected by means of trunk line T, which is shown in schematic form, to a secondary selector SS of the two-wire type which has brushes 6, 7 and 8. The secondary selector has access to a combination toll and local connector circuit C shown at the left of Fig. 2 having brushes 200, 201 and 202. The connector C has access to an intercepting operator's trunk IOT shown ending in jack

210 with which the intercepting operator's 55 cord OC is used. The dial 1 at the subscriber's station A in Fig. 1 is of a type disclosed in the patent to Erickson #909,382 and will not be described in detail here with the exception of calling attention to the fact 60 that impulses are sent first over one side of the line and then over the opposite side.

A clearer idea of the operation of these circuits may be had from the following detailed description. When the calling subscriber A removes the receiver from the switchhook the line switch LS operates in the manner well known in the art and connects subscriber A through to the first selector FS. Line switch LS closes a circuit from ground through the winding of relay 22 over lead 36 through the normal rotary contact of off-normal spring 37, conductor 38, winding of relay 13 to battery. Relay 13 operates and opens the talking leads and closes conductors 50 and 51 through for transmission of impulses to relays 21 and 30, but due to the resistance of relay 13, relay 22 does not operate. When the subscriber operates dial 1, impulses are sent from ground on the dial over conductor 27 through line switch LS, outer front contact of relay 13 through the winding of vertical relay 30 to battery. The vertical relay 30 closes a circuit from 70 ground on the middle contact of spring combination 29 through the winding of vertical magnet 23 to battery on the back contact of release magnet 24. Vertical relay 30 follows the impulses from the dial 1 and 75 transmits them to the vertical magnet 23 thereby stepping the first selector switch a 80 certain number of steps in a vertical direction to select a trunk group according to the 85 number dialed.

Following the transmission of the first series of impulses over line conductor 27, a single impulse is transmitted from ground at the dial, over conductor 28 through the line switch LS, through the inner front contact of relay 13 through the winding of rotary relay 21 to battery. Rotary relay 21 follows this impulse from the dial at subscriber's station A and connects ground through the middle contact of spring combination 29, through the winding of rotary magnet 26 to battery on the back contact of release magnet 24, thereby causing rotary 90 95 100 105

magnet 26 to operate. When rotary magnet 26 operates it closes the contacts of private magnet 25 which are mechanically connected as disclosed, thereby closing a circuit from battery on the back contact of release magnet 24, through the winding and outer front contact of private magnet 25, through the winding of release relay 27 to brush 5. This circuit is closed for purposes hereinafter described. After the impulse has been received by relay 21, it releases, opening the circuit of rotary magnet 26, which releases, in turn permitting the contacts of private magnet 25 to open if the trunk upon which brushes 3, 4 and 5 are resting is idle.

Should the first trunk of the group be busy, ground will be connected to contact 32 from another selector such as FS, thereby holding private magnet 25 operated over the circuit previously traced. A self interrupting circuit is now closed for rotary magnet 26 extending from battery at the back contact of release magnet 24, winding and contacts of magnet 26 to ground on the inner contact of private magnet 25. Magnet 26 rotates the brushes step-by-step over terminals of busy trunks. As soon as an idle trunk is found brush 5 encounters no ground and private magnet 25 releases opening the circuit of rotary magnet 26 causing the brushes of the selector to stop rotating. Upon the first rotary step, off-normal springs 37 operate. During the rotary movement of the selector relay 13 is held operated over a circuit extending from battery through the winding of relay 13, alternate contacts of springs 37, to ground at the inner contact of magnet 25. When the rotary movement ceases and magnet 25 deenergizes, the circuit of relay 13 is opened and it releases to disconnect the windings of relays 21 and 30 from the subscriber's line and to cut the line conductors through to the brushes 3, 4.

Assuming the trunk terminating in repeater R to be idle, a circuit will be closed from battery through relay 31, resistance 39, contact 32, brush 5 through the winding of relay 27 to ground on the outer back contact of private magnet 25, but due to the resistance 39, relays 27 and 31 do not operate at this time. A circuit is also closed from ground on the outer back contact of relay 25 through the winding of relay 27, brush 5, terminal 32, winding of relay 43, left back contacts of relays 40, 41 and 44, back contact of relay 43, right back contact of relay 19 to battery through relay 45. Relay 45 energizes in this circuit but relay 43 does not. The relay 45 closes a locking circuit for itself from battery, through its winding, and right front contact, contact of relay 49 to ground at the contact of magnet 25 over the circuit previously traced, and closes a circuit from battery through the winding

of relay 19, left front contact of relay 45, left back contact of relay 44 and thence over the circuit above traced to ground on the outer back contact of private magnet 25. Relay 19 operates and locks over a circuit from battery through its winding and right front contact, back contact of relay 43, left back contact of relay 44 and thence to the same ground hereinbefore traced. A circuit is closed for relay 16 over a parallel circuit from battery, through its left winding, left front contact of relay 45 and thence to ground on relay 25. Relay 16 does not receive sufficient current to operate at this time.

The operation of relay 19 closes a loop circuit for operating relay 33 in secondary selector SS. This loop may be traced from battery through the left winding of relay 33, outermost back contact of relay 9, conductors 52 and 14, coil 15, right winding of relay 16, conductor 17, left back contact of relay 18, left front contact of relay 19, conductor 57, middle back contact of relay 9 to ground through the right winding of relay 33. Relay 16 does not operate in this circuit due to the fact that its windings are in opposition with each other at this time.

When subscriber A operates the dial 1 for the second digit, impulses are received over brush 3 at first selector FS, over terminal 12, left back contact of relay 47 to battery through the winding of relay 18. Relay 18 follows the impulses and opens and closes the loop traced above. The operation of relay 18 also closes an obvious circuit for the operation of relay 34, which relay 34 being slow to release remains operated during pulsing and opens conductor 53 at its left back contact and at its left front contact short-circuits the right winding of relay 16 and coil 15 in order to eliminate their impedance from the loop while impulsing. The opening and closing of the above traced loop operates relay 33 which closes an obvious circuit for the operation of relay 20. Relay 20, being slow to release, remains operated during the impulsing period and closes a circuit for transmitting impulses over an impulse circuit from ground on the back contact of relay 9, back contact of relay 33, right front contact of relay 20, winding of relay 54 to battery through the winding of primary magnet 35, thereby stepping the brushes 6, 7 and 8 of a second selector SS to the desired group. Relay 54 operates but on account of its being a slow to release relay it does not follow the pulses but remains operated throughout the dialing period.

As soon as the off-normal contacts 36 are closed following the movement of the switch shaft one step in a vertical direction, a circuit is closed to operate relay 56 as follows: battery, through the winding of relay 56,

lower contact of off-normal springs 36, front contact of relay 54, left front contact of relay 20 to ground. Relay 56 operated locks as follows: battery, winding of relay 56, 5 lower contact of off-normal spring 36, back contact of secondary magnet 37, upper contact of relay 56 to ground on the right back contact of relay 9. The primary movement of the switch is completed at the end of the 10 impulse train and the impulse relay 33 remains operated, opening the circuit through the primary magnet 35 and relay 54, releasing the magnet and the relay. In releasing, relay 54 closes a circuit to operate the secondary magnet 37 as follows: battery, winding of secondary magnet 37, front contact of relay 56, back contact of relay 54 to ground at the left front contact of relay 20. The secondary magnet 37 in operating opens 15 at its contact the locking circuit for relay 56, thereby releasing it, relay 56 in turn opening the circuit of magnet 37. The operation and release of magnet 37 causes the brushes 6, 7 and 8 of selector switch SS to 20 advance one step to the first trunk terminals of the selected group. Should the first trunk be busy, ground will be found on the sleeve terminal (corresponding to terminal 224) and will be connected to brush 8. A circuit 25 will now be closed by way of the sleeve terminal of the busy trunk to reoperate relay 56 as follows: battery, winding of relay 56, lower contact of off-normal springs 36, back contact of secondary magnet 37, innermost 30 left back contact of relay 9, brush 8 to ground on the sleeve of the busy trunk. Relay 56 operated, locks over the locking circuit previously traced and closes the circuit 35 previously traced for the secondary magnet 37, which operates and again opens at its back contact the locking circuit for relay 56, releasing the relay which in turn opens the circuit for secondary magnet 37 which likewise releases. The release of magnet 37 40 advances brushes 6, 7 and 8 to the terminals of the next trunk in the group. This cycle of operations continues until an idle trunk is found.

Let us assume that the brushes 6, 7 and 8 45 are now resting upon terminals 208, 209 and 224 and that the connector C is idle, in which case terminal 210 will be free from ground. A circuit will now be closed to operate relay 9 as follows: battery, winding of 50 relay 56, lower contact of off-normal springs 36, back contact of secondary magnet 37, winding of relay 9 to ground through the left front contact of relay 20. Relay 56 will 55 not operate at this time due to the high resistance of the winding of relay 9. Relay 9 operated extends the connection by way of brushes 6 and 7 to terminals 208 and 209 through its left outermost and middle front contacts. The impulse relay 204 of the connector circuit C will now operate over a circuit 60 from battery through the left winding of relay 204, conductor 206, inner left back contact of relay 203, terminal 209, brush 6, middle front contact of relay 9, conductor 57, left contact of relay 19 left back contact of relay 18, conductor 17, right winding of relay 16, resistance 15, conductor 14, conductor 52, outer left front contact of relay 9, brush 7, terminal 208, outer left back contact of relay 203, conductor 205 to ground through the right winding of relay 204. Relay 204 is a pulsing relay and operates under control of relay 18 which is in turn under control of the subscriber's dial. Relay 204 operated, operates relay 207 over an obvious circuit. Relay 207 connects ground from its inner right front contact to terminal 224 thence over brush 8, the inner left front contact and winding of relay 9 to battery through the winding of relay 56 as previously traced for holding switch SS in its operated position and to prevent the connector C from being seized by another second selector. It is to be noted that upon the operation of relay 9, the circuit of relay 33 was opened whereupon relay 33 released in turn releasing relay 20. Relay 20 being slow to release, however did not open the circuit of relay 9 until after relay 9 became locked over brush 8. Relay 207 also opens the release circuit for the connector switch and prepares a circuit for the operation of the vertical magnet 214 through its outer right front contact, conductor 211, lower normal contact of the off-normal switch 212 through the winding of relay 213 and the winding of primary magnet 214 to battery. The first set of impulses sent out by the calling station after the seizure of this switch 105 operates relay 204 which operates the primary magnet 214 to step the shaft in a vertical direction and operates relay 213 in series with the primary magnet 214. Relays 207 and 213 remain operated during this 110 series of impulses since they are slow to release. When the shaft moves in accordance with the first digit in a vertical direction, the original circuit through the off-normal springs for operating primary magnet 214 is 115 transferred from the lower normal contact to the lower alternate contact of off-normal switch 212, and the left front contact of relay 213, which circuit is maintained due to the slow release action of relay 213. After all 120 the remaining pulses of this series sent out by the dial are finished, relay 213 releases and prepares a circuit for operating the secondary magnet 215, extending from battery through magnet 215, innermost right back contact of relay 216, inner right back contact of relay 217, left back contact of relay 213, lower alternate contact of off-normal switch 212, conductor 211, outer right front contact of relay 207 to ground on the back contact 125 130

of pulsing relay 204. The second set of impulses received by connector C from the calling station will now operate the secondary magnet 215 and rotate the shaft according to the number of impulses dialed. Relay 207 also remains operated during the operation of the secondary magnet on account of its slow release feature. Relay 218 also operates in the pulsing circuit in parallel with the secondary magnet 215 and due to its slow release feature remains operated during the pulsing period to close a circuit for testing the called trunk. This circuit may be traced from battery through the winding of relay 217, next to inner right back contact of relay 216, right front contact of relay 218, conductor 219 to brush 202. If the called line is busy, ground is found on terminal 220, thereby operating relay 217. Relay 217 operated, locks to ground upon the release of relay 218 over a circuit from battery, winding of relay 217, right back contact of relay 216, right back contact of relay 218, outer right front contact of relay 217, to ground at the inner right front contact of relay 207. The operation of relay 217 closes a circuit from ground through the winding of tone coil 223, left front contact of relay 217, conductors 225 and 240 terminal 209, brush 6, middle front contact of relay 9, conductor 57, left front contact of relay 19, left back contacts of relays 18 and 34, terminal 12, brush 3, outer back contact of relay 13, conductor 51, terminal of line switch LS conductor 27, subscriber's station A conductor 28, terminal of line switch conductor 50, inner back contact of relay 13, brush 4, terminal 11, right back contact of relay 47, to battery through relay 31, giving the subscriber a tone as an indication of a busy condition.

If the called trunk IOT is idle, battery will be connected to terminal 220, thereby preventing the operation of relay 217. Relay 216 will then operate in a circuit from battery, terminal 220, brush 202, right back contact of relay 218, right winding of relay 216, outer right back contact of relay 217, conductor 227 to ground on the inner right front contact of relay 207. Upon its operation relay 216 locks over its left winding and inner left contact, middle alternate contacts of off-normal springs 212, to ground at the left front contact of relay 207 and connects ground from its outer right front contact to brush 202, thereby making the intercepting operator's trunk IOT busy. Heretofore, relay 216 was only partially operated, the only contacts closed being the left innermost front contact and the outer right contact. With the closure of the locking circuit through its left winding, relay 216 completely operates its remaining contacts and is maintained energized until the switch releases. The operation of relay 216 connects

leads 228 and 229 to brushes 200 and 201 through its two outer left front contacts. The operation of relay 216 opens the circuit for the secondary magnet 215 through its innermost right back contact, thereby preventing any false pulses from stepping the switch further. It also opens the circuit for relay 217 at its next to inner right back contact, thereby preventing busy tone from being impressed upon the calling subscriber's line and also opens the circuit to prevent release magnet 235 from operating and releasing the connector.

Positive or negative superimposed ringing current is now impressed on the selected trunk through the outer right back contact of relay 230. This circuit may be traced from ringing current source 280 through the right winding of relay 230, outer right back contact of relay 230, conductor 229, left front contact of relay 216, brush 201, terminal 221, right back contact of relay 231, windings of relay 237, middle left back contact of relay 231, terminal 222, brush 200, outermost left contact of relay 216, conductor 228 to ground on the inner right back contact of relay 230. This ringing current causes the operation of relay 237, lighting lamp 238 in an obvious circuit. Relay 237 also locks in a circuit from battery on the outer left back contact of relay 231, left winding of relay 237 to ground on its left front contact, thereby holding relay 237 operated after the ringing current ceases.

When the intercepting operator inserts the plug of cord 232 into jack 210 in response to the lamp signal 238, relay 233 operates over a circuit from battery through the winding of relay 233, right back and left back contacts of relay 241, thence over the ring of plug 232, ring of jack 210, inner left back contact of relay 231 to ground. Another circuit will be closed from battery, through the left back contact of relay 242, conductor 253, winding and left back contact of relay 244, left back contact of relay 241, thence over the circuit above traced to ground through the inner left back contact of relay 231. The operation of relay 244 closes a circuit for the operation of relay 231 from ground through the winding of relay 231, sleeve of jack 210, sleeve of cord 232, left front contact of relay 244, winding of relay 244, conductor 253, to battery on the left back contact of relay 242. The operation of relay 231 opens the circuit for relay 237, thereby releasing it and extinguishing lamp 238, and closes the ring of jack 210 through its inner left front contact to terminal 221. The operation of relay 244 closes a holding circuit for relay 233 from ground on the inner right front contact of relay 244, right back contact of relay 241 to battery through the winding of relay 233, and a circuit from the ringing source 280 through

the right winding and outer right back contact of relay 230, left middle outer front contact of relay 216, brush 201, terminal 221, inner left front contact of relay 231, rings 5 of jack and plug, left back contact of relay 241 to ground at the inner right front contact of relay 244. Relay 230 locks over its left winding and contact to ground on the left front contact of relay 207. The operation 10 of relay 230 disconnects the ringing source and ground from the conductors 228 and 229 and closes the talking circuit through its contacts. The operation of relay 244 also closes a circuit for operating the 15 slow operating relay 245 which operates slow operating relay 241. These two relays are slow to operate to allow the left back contact of relay 241 to remain closed a sufficient length of time to operate relay 230 in 20 the connector C, before the contacts open. The operation of relay 233 also opens the tip of the cord and operates the slow to release relay 243 in an obvious circuit through its left front contact. Relay 243 in turn operates relay 234 over an obvious circuit. 25

By this time relay 241 is completely operated thereby opening the holding circuit for relay 233 allowing it to release in turn releasing slow release relay 243. Relay 243 30 is slow enough to keep relay 234 operated a sufficient length of time to send an impulse of ringing circuit from generator 246 to operate relay 49 in the repeater 11. This circuit is traced from generator 246 right front 35 contact of relay 234 right back contact of relay 233 tips of cord 232 and jack 210, terminal 222, brush 200 outer left front contact of relay 216, conductor 228, inner right front contact of relay 230, conductor 239, 40 terminal 208, brush 7, outer left front contact of relay 9, conductor 52, right back contact of relay 34, winding of relay 49, to ground on the outer right back contact of relay 44. Relay 49 operated, opens the locking circuit for relay 45 which closes an operating circuit for relay 47 from ground on terminal 32, winding of relay 43, left back contacts of relays 40, 41 and 44, back contact of relay 43 as this is slow to operate, right 45 front contact of relay 19 left back contact of relay 45, to battery through relay 47. Relay 47 operated, connects talking battery back to the calling subscriber's line A through the windings of relay 44. Relay 44 50 operates in a circuit extending from battery through its left winding, the left contact of relay 47, terminal 12, brush 3, thence to the calling line, returning over brush 4, terminal 11, inner right front contact of relay 47, right winding of relay 44 to ground. Relay 44 in operating establishes a locking circuit for relay 47 from battery, winding and outer right contact of relay 47 to ground at the outer right front contact of relay 44, and 55 closes a circuit for relay 40 extending from

battery through the winding of relay 40 to ground at the inner right contact of relay 44. With relays 44 and 47 operated relay 19 is held operated over a circuit extending from battery through the winding of relay 19, left back contact of relay 45, to ground through the outer right contacts of relays 44 and 47. Relay 40 closes an obvious circuit for relay 41 which at its right contact closes an additional holding circuit for relay 19 70 extending from ground at the right contact of relay 41, left front contact of relay 44, back contact of relay 43, thence to battery through the winding and right front contact of relay 19. Relay 40 upon operating also 75 opens the circuit extending through the winding of relay 43 to terminal 32 which is later effective for releasing switch FS. The operation of relay 44 also opens the circuit 80 of relay 49. 85

At the cord circuit upon the operation of relay 241 a bridge circuit consisting of relays 250 and 251 and coil 236 was connected across the tip and ring of the cord. The operation of relay 241 also opens the circuit 90 for relay 233. 95

When the tip and ring of the cord are closed by the operation of relay 241 a circuit is closed for operating relay 251 from battery through the right winding of relay 203, conductor 239, inner right front contact of relay 230, conductor 228, outermost left front contact of relay 216, brush 200, terminal 222, tip of jack 210, tip of cord 232, right back contacts of relays 233 and 234, conductor 235, coil 236, windings of relays 250 and 251, conductor 249 left front contact of relay 241, ring of cord 232, ring of jack 210, inner left front contact of relay 231, terminal 221, brush 201, left front contact of relay 216, conductor 229, outer right front contact of relay 230, conductor 240 to ground through the left winding of relay 203. Relays 203 and 250 do not operate in this circuit as the resistance of relay 250 is too high to allow relay 203 to operate and the battery polarity is not correct for the operation of relay 250. Relay 203 fails to operate on a call to an operator but does operate on a station to station call as described hereafter. 105 110 115

Should a call be initiated to a subscriber in a two-wire office (not shown) instead of to an intercepting operator, the brushes 200, 201 and 202 will come to rest on the tip, ring and sleeve terminals, respectively, of a subscriber's station (not shown). The operation of the first selector, repeater, second selector and connector will be the same as described above up to and including the connection of ringing source 280 to the subscriber's line. When the called subscriber answers, relay 230 operates and disconnects the ringing current as described above. Relay 203 will also operate in a circuit from 120 125 130

ground through its left winding, conductor 240, outer right front contact of relay 230, conductor 229, left front contact of relay 216, brush 201, through the subscriber's loop, brush 200, outer left front contact of relay 216, outer right front contact of relay 230, conductor 239 to battery through the right winding of relay 203. Relay 203 operates and closes a locking circuit for relay 230 and reverses the circuit for relay 204 hereinbefore traced through the right winding of relay 16. As the windings of relay 16 are now aiding each other, the relay will operate and in turn operate relay 47 over an obvious circuit. The operation of relay 47 connects the windings of relay 44 across the brushes 11 and 12 for supplying talking battery to the calling subscriber. Relay 44 will operate in this circuit and close an obvious circuit through its inner right front contact for operating relay 40. Relay 40 in turn operates relay 41 over an obvious circuit and opens the disconnect circuit hereinafter described. Relay 44 also closes a locking circuit for relay 47 from ground on its outer right front contact and winding of relay 47 to battery thereby holding the relay operated until the called subscriber disconnects.

When the call is finished and the calling subscriber hangs up ground is connected momentarily to both sides of the line at substation A thereby holding relay 44 operated. When relay 44 finally releases the locking circuit for relay 47 is opened releasing the relay thereby opening the holding circuit for relay 19. The release of relay 44 also opens the circuit for relay 40 in turn releasing relay 41. Both of these relays are slow to release but the adjustment of relay 40 is such that it will release before relay 41. Therefore a circuit will be closed from battery through resistance lamp 42, left front contact of relay 41, left back contact of relay 40, winding of relay 43, terminal 32, brush 5, release relay 27 to ground at the right front contact of relay 25. The release magnet 24 is now operated over a circuit from battery thru the winding of release magnet 24, front contact of relay 27, conductor 36 to ground thru relay 22 in the line switch. The operation of the release magnet 24 restores the apparatus of the first selector FS to normal. The operated relays of the repeater R are now in normal condition.

Upon the release of relay 19 the circuit of relay 204 of connector C is opened. The release of relay 204 releases relay 207 and relay 216 thereby closing a circuit for the operation of release magnet 255 which extends from battery, winding of magnet 255, upper contacts of off-normal switch 212, back contacts of relays 216, 207 and 204 to ground. The operation of release magnet 255 causes the brushes of connector C to be restored to normal. The release of relay 207 discon-

ncts ground from terminal 224 allowing relay 9 to release. Relay 9 released closes a circuit from ground over its right back contact, left back contact of relay 33, right back contact of relay 20, upper alternate contact 70 of spring 36, to battery through the release magnet 55. The release magnet 55 causes the brushes of the second selector SS to return to normal.

Relay 207 released also opens the locking circuit for relay 230. The release of contacts 222, 221 and 220 by brushes 200, 201 and 202 opens the loop circuit for relay 251 hereinbefore traced. The release of relay 251 closes a circuit for relay 242 from ground 80 on the inner right front contact of relay 244, right front contact of relay 241, left back contact of relay 234, back contact of relay 251 to battery through the winding of relay 242 operating it. The operation of relay 242 lights lamp 265 as a signal to the intercepting operator to disconnect, opens the circuit of relay 244 and establishes an alternative circuit from battery through the left front contact of relay 257, sleeves of plug 90 232 and jack 210 to ground through relay 231. Relay 257 energizes to establish an obvious holding circuit for relay 242 for maintaining lamp 265 lighted after relay 244 releases, in turn releasing relays 245 85 and 241.

In response to the illumination of disconnect lamp 265, the operator withdraws plug 232 from jack 210, releasing relays 231 and 257, relay 257 in turn releasing relay 242 100 and extinguishing the lamp 265. All apparatus is now in normal condition.

What is claimed is:

1. In a telephone system, a subscriber's station, an operator's position, means including switching mechanism for extending a connection from said subscriber's station to said operator's position, means associated with said switching mechanism for supplying talking battery to said subscriber's station, a cord circuit at said operator's position for further extending said connection, and means operative in response to the association of said cord circuit with said extended connection to render effective said talking battery supplying means.

2. In a telephone system, a subscriber's station, an operator's position, means including switching mechanism and a repeater for extending a connection from said subscriber's station to said operator's position, means associated with said repeater for supplying talking battery to said subscriber's station, a cord circuit at said operator's position for further extending said connection, and means operative in response to the association of said cord circuit with said extended connection to render effective said talking battery supplying means.

3. In a telephone system, a subscriber's sta-

tion, an operator's position, means including switching mechanism and a repeater for extending a connection from said subscriber's station to said operator's position, means associated with said repeater for supplying talking battery to said subscriber's station comprising a source of talking current, a relay for connecting said source of current to that part of said connection extending to said subscriber's station, and a relay responsive to ringing current for controlling said first relay, a cord circuit at said operator's position for further extending said connection, a source of ringing current at said cord circuit, and means operative upon the association of said cord circuit with said extended connections to apply said ringing current source to said cord circuit whereby said second relay is operated.

20 4. In a telephone system, a subscriber's station, an operator's position, means including switching mechanism and a repeater for extending a connection from said subscriber's station to said operator's position, means associated with said repeater for supplying talking battery to said subscriber's station comprising a source of talking battery and means initially responsive to ringing current to connect said source to said subscriber's station, a cord circuit at said operator's position, a source of ringing current in said cord circuit, and means momentarily operative upon association of said cord circuit with said extended connection to apply said

ringing current source to said cord circuit 35 whereby said talking battery source is connected to said subscriber's station.

5. In a telephone system, a subscriber's station in a three-wire office, an operator's position in a two-wire office, means including 40 switching mechanism for extending a connection from said subscriber's station to said operator's position, means associated with said switching mechanism for supplying talking battery to said subscriber's station, 45 a cord circuit at said operator's position for further extending said connection, and means operative upon the association of said cord circuit with said extended connection to render effective said talking current supply means.

6. In a telephone system, a subscriber's station in a three-wire office, an operator's position in a two-wire office, means including 55 switching mechanism and a repeater for extending a connection from said subscriber's station to said operator's position, means associated with said repeater for supplying talking battery to said subscriber's station, a cord circuit at said operator's position for 60 further extending said connection, and means operative upon the association of said cord circuit with said connection to render effective said talking battery supply means.

In witness whereof, we hereunto subscribe 65 our names this 3d day of June, A. D., 1925.

EMIL JACOBSEN.
ARTHUR B. SPERRY.
